(57) **CLAIM**

I claim, the ornamental design for a table base, as shown and
described.

DESCRIPTION

FIG. 1 is a perspective view of a table base, showing my new
design;

FIG. 2 is a side view thereof, the opposite side view being
a mirror image thereof;

FIG. 3 is a front view thereof, the opposite rear view being
a mirror image thereof;

FIG. 4 is a top view thereof;

FIG. 5 is a bottom view thereof;

FIG. 6 is a perspective view thereof, showing a second
embodiment of my new design;

FIG. 7 is a side view thereof, the opposite side view being
a mirror image thereof;

FIG. 8 is a front view thereof, the opposite rear view being
a mirror image thereof;

FIG. 9 is a top view thereof;

FIG. 10 is a bottom view thereof;

FIG. 11 is a perspective view thereof, showing a third
embodiment of my new design;

FIG. 12 is a side view thereof, the opposite side view being
a mirror image thereof;

FIG. 13 is a front view thereof, the opposite rear view being
a mirror image thereof;

FIG. 14 is a top view thereof; and,

FIG. 15 is a bottom view thereof.

1 Claim, 15 Drawing Sheets
